UNITED STATES PATENT OFFICE

FRANK E. JAMISON, OF KANSAS CITY, KANSAS

MULTICOLOR PRINTING PRESS

Application filed October 27, 1930. Serial No. 491,452.

This invention relates to multi-color printing presses, and has for its primary object to produce a construction whereby the printing plates can be placed on or removed from the respective cylinders without adjustment or removal of any of the inking rolls or mechanism.

A still further object is to produce a press of simple, strong, durable and relatively economical construction; and with these general objects in view and others as will hereinafter appear, the invention consists in certain new and useful features of construction and combination of parts as hereinafter described and claimed; and in order that it may be fully understood, reference is to be had to the accompanying drawings, in which:—

Figure 1 is a fragmentary side elevation of a multi-color printing press embodying the invention.

Figure 2 is a plan view of the same.

In the said drawings, where like reference characters identify corresponding parts in all of the figures, the side frames of the press consist of stand members 1, two horizontal top members 2 and cap members 3, each bridging a central space between the respective top members and securing between them upon the stand members, opposite blocks 4 forming bearings for the shaft 5 of an impression cylinder 6 common to all of the form cylinders, as will hereinafter appear, the impression cylinder having the customary blanket cover 7, and being driven by power means (not shown) applied to shaft 5 in any conventional or suitable manner.

As shown in the drawings, there are four form cylinders 8 arranged around the impression cylinder, the shafts 9 of two of said cylinders being journaled in bearings 10 secured to opposite edges of the stand members 1. The shaft 9 of the other two form cylinders is journaled in bearings 11, mounted on pairs of oppositely inclined arms 12 of the top members 2.

It will be noted that more than fifty percent of the peripheral surfaces of the form cylinders are always beyond or outside of adjacent parts of the press and that the plates

12a removably secured therein in pairs, in any suitable or conventional manner, as by the conventional clamps 12b, are accessible without necessitating the removal or adjustment of any part of the press other than effecting such rotation of the impression cylinder, and hence of the form cylinders, as to fully expose the respective plates in the event the operation of the press is arrested with one of said plates in a position where it cannot be readily reached for replacement or other purposes.

As a press of this character, of desirable size for printing comic sections of newspapers, is too high for an attendant, standing on the floor, to secure a plate in or remove it from position on the two topmost form cylinders, the stand members may be provided with elevated platforms, not shown, upon which the attendant may stand. No stands are needed as regards the two lower form cylinders, as they are within convenient reach from the floor. It will be understood that the reference to the height of the press, is not intended as a limitation, as the matter of where the attendant stands when securing the plates on or removing them from operative position or in doing other work about the press is unimportant and is referred to herein as indicating that the press may be of small size as compared to other multi-color presses for turning out work of the same character.

Coaxial and rotatable within and at the same speed as and disposed at one end of the impression cylinder, is a large gear wheel 13, intermeshing with gear wheels 14 coaxial and rotatable with the form cylinders.

The various mechanisms for supplying ink or desired colors from the respective inking rollers to the plates on the form cylinders, may be of any suitable or conventional type, connected by trains of gearing 16 (only one being shown) to the large gear wheel of the impression cylinder, which gearing requires no adjustment or shifting when a form roller plate or plates is to be placed in or removed from position, and the same statement applies to the in-distributing rollers 17 for the transfer of ink from the inking rollers to

the plates of the respective form cylinders. The paper web P, encompasses the impression cylinder for the greater part of its periphery, and preferably leads to and from the lower part of said cylinder and over guide rollers 18, journaled in the stand member.

All of the form rollers, are adjustable toward and from the impression cylinder to compensate for wear and impression, and the plates thereon are likewise adjustable circumferentially, not shown, to insure proper and accurate registration of the different colors printed upon the web as it passes the respective plates.

The conventional and generally used multi-color presses for newspaper comic sheet printing are tall and expensive, and all such presses, as far as I am aware, are objectionable in that adjustments and replacements of the plates relative to the form cylinders, not only necessitate the conjoint attention of two operators, but adjustment or shifting of parts carrying the gearing, ink and the distributing rollers, and in the standard types of such presses such adjustment or shifting operations consume several hours and during such period the press is idle. With the press herein described and shown, permitting change of plates without necessitating any adjustment to place the plates in proper operative relation, several hours running time is saved each week. In other words, several thousand more papers can be printed per day with this press than with presses of the type mentioned, running at the same speed. Furthermore the construction and size of the press are such that it can be transported or shipped if necessary, as a single unit, and when shipped in knock-down condition, can be erected or assembled for operation in a very short time and at low cost as compared with the conventional type of multi-color press for printing comic sheets or supplements for newspapers.

From the above description, it will be apparent that I have produced a multicolor printing press embodying the features of advantage set forth as desirable in the statement of the objects of the invention, and which may be changed in minor particulars without departing from the spirit and scope of the appended claims.

I claim:

1. In a multi-color printing press, comprising a stand member, an impression cylinder supported from and at the upper end of the stand member, oppositely-projecting top members upon the stand member and spaced apart at their inner ends, the top members having upwardly-diverging arms equi-distant from and at opposite sides of the axis of the impression cylinder, bearings upon the said arms, form cylinders journaled in said bearings and geared to the

impression cylinder, each form cylinder bearing such relation to the impression cylinder and to its respective supporting arm as to always make accessible more than fifty-percent of its circumference.

2. In a multi-color printing press, a stand member, a pair of top members upon and projecting laterally beyond opposite sides of the stand member, bearing blocks upon the stand member and between the top members, a shaft journaled in said blocks, an impression cylinder mounted on the shaft, upper and lower sets of form cylinders arranged around and geared to the impression cylinder; the lower form cylinders projecting for more than half of their circumferential areas, beyond opposite side edges of the stand member and below the plane of the top members and always accessible, and plates on the accessible areas thereof, the upper form cylinders occupying a plane above the top members and having more than half of their circumferential areas at all times exposed and accessible and plates secured on the accessible areas thereof; a set of ink-distributing rollers for engagement with each form cylinder at a point beyond the said exposed and accessible circumferential area thereof, and means for transmitting power from the impression cylinder to the ink-distributing rollers.

In testimony whereof I affix my signature.

FRANK E. JAMISON.
